UNITED STATES PATENT OFFICE.

RUSSELL R. SMITH, OF RODEO, CALIFORNIA.

AEROPLANE.

1,133,757.

Specification of Letters Patent. Patented Mar. 30, 1915.

Application filed May 9, 1914. Serial No. 837,452.

To all whom it may concern:

Be it known that I, RUSSELL R. SMITH, a citizen of Canada, residing at Rodeo, in the county of Contra Costa and State of California, have invented certain new and useful Improvements in Aeroplanes, of which the following is a specification.

My invention relates to the class of aeroplanes, and particularly to that type in which the stabilizing planes or ailerons are automatically operated by a pendulously suspended car or body.

The object of my invention is to provide such a relative arrangement and fashioning of the main planes and the stabilizing planes, that in an emergency all the planes may together be converted into an effective parachute, and to this end my invention consists in the novel aeroplane which I shall now fully describe by reference to the accompanying drawings, in which—

Figure 1 is a longitudinal sectional view of my aeroplane. Fig. 2 is a front view of the same, the propeller being removed. Fig. 3 is a top plan of the same, on a reduced scale. Fig. 4 is a detail view, taken on line $x-x$ of Fig. 1, of the means for locking the main planes and the car against relative movement.

1 are the main planes. These converge upwardly and meet at an angle the degree of which is, in general, determined by the double function which said planes are intended to perform, namely, that of aeroplanes, and that of a parachute. Such angle is, therefore, selected as will give to one function as much power and effect as may be consistent with the exercise of the other function, and this selection is subject to such latitude as experience may suggest.

2 are the stabilizing planes or ailerons. These also have a double function, namely, that of equilibration, and that of a parachute; and because of these functions the superficial dimensions of said ailerons are necessarily relatively large, and approach quite nearly those of the main planes, as seen in Fig. 3. The ailerons lie along the rear edges of the main planes 1 and when at rest normally conform to and continue the planes thereof. They are connected with the main planes by a hinge joint which will permit them to be drawn down to an angle with the main planes and to return therefrom. I have, for illustration, shown this

joint as made by hinges 3 and controlling springs 4.

5 is the body or car of the machine. This is pivotally suspended from the main planes, in accordance with that type of automatically balancing aeroplanes in which a pendulous action is employed. The connection is formed by a frame 6 rising rigidly from the body or car, and pivoted above at 7, in the fore and aft line of the angle or apex of the main planes. The connections between the pendulous car and the ailerons, by which the latter are operated, to automatically perform their stabilizing or balancing function, consist of the two lines 8. One of these lines is at one end made fast to one side of the car at 8' and thence by means of a guide-pulley 9 is directed to a fastening at 10 to the aileron on the opposite side of the machine. The other line is correspondingly directed. These lines, as stated, effect the ordinary operation of the ailerons to balance the machine in flight. What may be termed the extraordinary or emergency operation of the ailerons to make them, in conjunction with the main planes, serve as a parachute, is effected by means of connections which are set in action by the aviator to meet the emergency, and by which the ailerons are drawn down far enough, as indicated by the dotted lines in Figs. 1 and 2, to constitute with the main planes a sufficiently effective parachute to insure safety. These connections may be of any suitable character, though for the sake of illustration, I have here shown them as comprising lines 11, which are secured at one end to the ailerons, and at the other end are wound upon a drum 12 to be driven by suitable power, say, for example, by a motor 13, which is under the control of the aviator.

In order to lock the pendulous car and the main planes together to preserve their normal position and prevent accident to the planes in alighting, I have a locking lever 14, under the control of the operator, said lever being adapted to be thrown into engagement with a keeper notch 15 on a cross bar 16 rigidly connecting the main planes.

17 indicates the motor of the machine and 18 is the propeller. 19 is the tail-vane and 20 is the rudder. 21 are the wheels, 22 are guard runners, and 23 is a rear support.

In normal flight, the operation of the machine is that which is customary. In case of

accident, by which this normal flight is interrupted, the aviator draws down the ailerons, thereby converting the planes 1 and ailerons 2 into a parachute.

5 I claim:—

1. In an aeroplane, the combination of upwardly converging main planes; stabilizing planes hingedly connected with the rear edges of the main planes, and adapted to be drawn down to an angle with the main planes, said stabilizing planes being fashioned and disposed relatively to the main planes to form a parachute therewith when drawn down in unison; a car pendulously suspended from the apex of the main planes; lines connecting the stabilizing planes with opposite sides of the car for automatically operating said planes as ailerons; and means under the control of the operator for simultaneously drawing down the stabilizing planes to form a parachute with the main planes.

15 2. In an aeroplane, the combination of upwardly converging main planes; stabilizing planes hingedly connected with the rear edges of the main planes, and adapted to be drawn down to an angle with the main planes, said stabilizing planes being fashioned and disposed relatively to the main planes to form a parachute therewith when drawn down in unison; a car pendulously suspended from the apex of the main planes; lines connecting the stabilizing planes with opposite sides of the car for automatically operating said planes as ailerons; and means under the control of the operator for simultaneously drawing down the stabilizing planes to form a parachute with the main planes.

20 3. In an aeroplane, the combination of upwardly converging main planes; stabilizing planes hingedly connected with the rear edges of the main planes, and adapted to be drawn down to an angle with the main planes, said stabilizing planes being fashioned and disposed relatively to the main planes to form a parachute therewith when drawn down in unison; a car pendulously suspended from the apex of the main planes; lines connecting the stabilizing planes with opposite sides of the car for automatically operating said planes as ailerons; and means under the control of the operator for simultaneously drawing down the stabilizing planes to form a parachute with the main planes, comprising a driven 30 drum and lines wound thereon and connected with the stabilizing planes.

35 4. In an aeroplane, the combination of upwardly converging main planes; stabilizing planes hingedly connected with the rear edges of the main planes, and adapted to be 40

45

drawn down to an angle with the main planes, said stabilizing planes being fashioned and disposed relative to the main planes to form a parachute therewith when drawn down in unison; a car pendulously suspended from the apex of the main planes; lines connecting the stabilizing planes with opposite sides of the car for automatically operating said planes as ailerons; means under the control of the operator for simultaneously drawing down the stabilizing planes to form a parachute with the main planes, and means for locking the car and the main planes against relative movement.

50 5. In an aeroplane, the combination of upwardly converging main planes; stabilizing planes hingedly connected with the rear edges of the main planes, and adapted to be drawn down to an angle with the main planes, said stabilizing planes being fashioned and disposed relatively to the main planes to form a parachute therewith when drawn down in unison; a car pendulously suspended from the apex of the main planes; lines connecting the stabilizing planes with opposite sides of the car for automatically operating said planes as ailerons; and means under the control of the operator for simultaneously drawing down the stabilizing planes to form a parachute with the main planes, and means for locking the car and the main planes against relative movement, comprising a lever mounted on the car and a cross bar carried by the main planes and having a keeper notch with which the lever engages.

55 In testimony whereof I have signed my name to this specification in the presence of two subscribing witnesses.

RUSSELL R. SMITH.
